UNITED STATES PATENT OFFICE

FRED G. SCHWEISTHAL, OF CHICAGO, ILLINOIS, ASSIGNOR TO STEWART-WARNER CORPORATION, OF CHICAGO, ILLINOIS, A CORPORATION OF VIRGINIA

FUEL PUMP

Application filed March 31, 1930. Serial No. 440,375.

The purpose of this invention is to provide an improved and economically constructable device for pumping fuel to the carburetor of a motor vehicle engine from the main fuel supply tank located at a lower level than the carburetor, utilizing for that purpose the engine ignition circuit and specifically the ignition coil unit in which the interruptions of the circuit alternately energizing and de- energizing the magnetic core, adapts the latter to constitute means for producing vibration or pulsation of a motor which may thereby become a pumping element by association with suitable valves and conduits. The invention consists in the elements and features of construction shown and described as indicated in the claims.

In the drawings:—

Figure 1 is a diagrammatic view for showing in their relative positions on the vehicle the main fuel supply tank, the carburetor and the pumping device of this invention.

Figure 2 is a vertical axial section of the ignition coil unit and the pump casing upon which it is mounted, the connection of the pump casing with the fuel source and the engine carburetor float bowl being indicated diagrammatically.

Figure 3 is a top plan view of the construction shown in Figure 2.

Figure 4 is a wiring diagram of the construction shown in Figure 2.

In the structure as illustrated in the drawings, A represents the main fuel supply tank at a lower level than the carburetor which is shown at B. The ignition coil unit is indicated in totality by reference character, C, said entire unit being commonly called the "ignition coil", and being hereinafter referred to by that term. Referring to Figure 2, the ignition coil unit is shown comprising a casing, 20, having a magnetic element consisting of a central pole member, 30, which constitutes the solenoid core, encompassed by the primary and secondary windings indicated at 40 and 41, respectively, with the usual paper insulation, indicated at 31, said magnetic element comprising also the outer pole member, 31, which embraces the solenoid windings, said outer pole mem-

ber being extended beyond the solenoid windings and beyond the plane of the end of the central core pole member, which also protrudes from the windings; and said outer pole member is furnished with an annular pole piece, 32, which may be referred to also as a flux ring, having its central aperture in alignment with the solenoid core pole member, 30. This central aperture of the flux ring is of suitable diameter to admit an armature indicated at 50, without contact with said flux ring, 32.

The pump body mounted upon or having mounted upon it the ignition coil unit, as mentioned, comprises a main casing member, 51, containing the pumping chamber, 55, having inflow and outflow connections hereinafter mentioned, having an aperture, 51^a, in its upper side through which the pumping member, hereinafter more particularly described, is admitted, said aperture being provided with a closure plate, 52. The casing member, 51, is recessed, as seen at 54, opposite the aperture which is closed by the closure member, 52, to form the pumping chamber. 70 The casing member, 51, is formed with an inflow duct, 56, leading into the pumping chamber at the right hand side (referring to Figure 2) and the outflow discharge duct, 57, leading from the opposite side of said pumping chamber. The inflow duct, 56, leads from an intake port, 59, at which there is provided an intake valve, 60; and the discharge port, 62, at which there is provided a discharge valve, 63, said intake and discharge valves being of customary construction arranged for inflow and outflow respectively, and seating against reverse flow, and being held normally thus seated by the springs, 64 and 65, respectively.

The drawings indicate that the fuel arrives at the pump by way of a pipe connection indicated at 67 at the right hand end of the pump casing and through which it is delivered into a fuel and sediment trap indicated at M, from which, upon the trap being filled to the inlet of the intake valve seating bushing, 68, it is withdrawn by the suction into the pumping chamber, 55. The drawings further indicate that there is provided 95 100

on the discharge line beyond the discharge valve, 63, a pressure trapping chamber, N, the provision of the fuel and sediment trap and pressure trap, M, N, respectively, and the relation of these features to the remainder of the pump construction, are not part of the present invention which is, however, adapted to be embodied in a construction having such features, as shown in the drawings.

10 The pumping member in the pumping apparatus as shown consists of a flexibly expandible and reducible chambered member indicated in totality at 70, which numeral specifically denotes also its interior cavity, said member being formed by a pair of concentrically corrugated disks, 71 and 72, clinched together and sealed at their periphery for enclosing a chamber between them.

In the construction shown the upper corrugated disk, 71, has a central aperture at whose margin said disk is made fast and sealed by means of an open nipple, 71^a, to a correspondingly centrally aperture and corrugated disk, 73, which spans the central aperture, 51^a, of the pump casing, said disk, 73, being dished confirming to the form of the under side of the closure plate, 52, intruding into the central aperture, 51^a, and having a marginal flange, 73^a, said disk being clamped by said marginal flange between the pump casing and its closure member, 52; and the latter has a central aperture, 52^a, at which the movable armature member, 50, is mounted by means of a stem, 50^a, which extends down through the registered central apertures of the disks, 71 and 73, and is made fast at its lower end to the lower disk, 72, of the pumping diaphragm structure to which said stem is clamped by inner and outer clamping nuts, 75 and 76.

As shown, and as a matter of convenience for assembling the parts, the annular pole piece, 32, is mounted in proper position both with respect to the pump casing and with respect to the fixed core of the solenoid by being lodged upon the upper ends of an upwardly protruding annular flange, 52^c, of the closure member, 52, and upwardly protruding bosses, 52^d, to the latter of which said pole piece is secured by screws, 32^e; and being thus secured, said pole piece serves for stopping the upper end of a spring, 75, which reacts at its lower end on an upwardly facing shoulder of a flange, 50^b, formed at the lower end of the movable armature, 50, said spring thus operating for holding the armature normally withdrawn from the central core member, 30, against the magnetic attraction of the latter when the solenoid is energized.

60 The operation of the construction as above described may be understood from the foregoing description to be that when the ignition coil windings are energized the armature, 50, is attracted to the core member, 30; and upon the interruption of the circuit it is retracted

by the reaction of the spring, 75, the alternate attracted and retracted movement of the armature operating respectively for reducing and expanding the pumping member, 70, the reduction of said member operating for increasing the fluid capacity of the pumping chamber and thereby operating for suction to draw in the fuel supply past the intake valve, 60, and the enlarging of the pumping member operating for reducing the fluid capacity of the pumping chamber and causing discharge of fuel past the outlet valve, 63.

I claim:

1. A pumping apparatus comprising in combination a solenoid structure, a pump casing on which the solenoid structure is mounted, said pump casing having a pumping chamber, a pumping member in said chamber arranged to be actuated for enlarging and reducing the fluid capacity of the chamber, the magnet element of the solenoid structure having a pole member formed and arranged for encompassing a movable armature, and an armature dimensioned for being thus encompassed carried by the pumping member, the pump casing being mounted with respect to the solenoid structure for positioning the pumping member suitably for carrying the armature in position for being encompassed by said pole member and reciprocating therein.

2. A pumping apparatus comprising in combination a solenoid, a pump casing on which the solenoid is mounted having a pumping chamber, a pumping member in said chamber arranged to be actuated for enlarging and reducing the fluid capacity of the chamber, the solenoid outer pole being extended beyond the plane of the central pole and furnished with an annular pole piece, and an armature carried by the pumping member mounted normally protruding through the central aperture of said pole piece and reciprocating therein in the pumping movement of said pumping member.

3. A solenoid structure having a magnetic core constituting one pole of the magnet with an opposite pole consisting of a member embracing the solenoid windings and extending protrudingly past the plane of the central core pole and furnished with an annular pole piece having its central aperture in alignment with the core pole; a pump casing on which said solenoid structure is mounted having a pumping chamber with a pumping member therein arranged to be actuated for enlarging and reducing the fluid capacity of the chamber; an armature carried by said pumping member for adapting it to respond to magnetic attraction by chamber-capacity-changing movement, said pumping member being positioned with respect to the solenoid structure for pumping movement toward and from the solenoid core pole, and said armature being dimensioned and arranged for extend-

ing through the annular pole piece and reciprocating therein toward and from the core pole, and a spring reacting on the armature and pumping member in opposition to the magnetic attraction of the solenoid magnet poles.

4. A pumping apparatus comprising in combination a solenoid structure; a pump casing on which said solenoid structure is mounted, said casing having a pumping chamber; a pumping member in said chamber arranged to be actuated for enlarging and reducing the fluid capacity of the chamber, the magnet element of the solenoid structure having a pole member terminating proximate to the pumping chamber; a movable armature carried by the pumping member in position exposed outside the pumping chamber toward and proximate to a fixed pole of the magnet element of the solenoid structure, the pumping member being arranged for movement in chamber enlarging direction by the movement of the armature under attraction of the magnet element when the solenoid is energized, and the spring reacting on the armature for reverse movement; whereby the intake stroke of the pump is affected by the magnetic attraction, and the discharge stroke is limited by the reaction of the spring.
5. In the construction defined in claim 4, the pumping member being a flexibly expansible and reducible chambered member, so that its expansion reduces and its reduction enlarges the fluid capacity of the pumping chamber, said pumping member being mounted in the pumping chamber by its wall at the side toward the magnet pole of the solenoid structure, and the armature being carried by the opposite wall, the first mentioned wall having an aperture and the armature having a stem extending through the aperture for reaching and securement to said opposite wall of the pumping member.
6. The construction defined in claim 1 having the pumping member consisting of a flexibly expansible and reducible chambered member having a nipple by which it is mounted at one side wall of the pumping chamber with said nipple affording atmospheric communication for venting the cavity of said member, the armature being carried by the opposite side wall of said expansible and reducible chamber.

In testimony whereof, I have hereunto set my hand at Chicago, Illinois, this 17th day of March, 1930.

FRED G. SCHWEISTHAL.
